UNITED STATES PATENT OFFICE.

WASHINGTON W. PIERCE, OF HUNTSVILLE, ALABAMA.

DESIGN FOR A BUTTON.

SPECIFICATION forming part of Design No. 25,655, dated June 23, 1896.

Application filed May 2, 1896. Serial No. 590,030. Term of patent 7 years.

To all whom it may concern:

Be it known that I, WASHINGTON W. PIERCE, a citizen of the United States, residing at Huntsville, in the county of Madison and State of Alabama, have invented and produced a new and original Design for a Button, of which the following is a specification, reference being had to the accompanying drawing, forming a part thereof.

10 The drawing represents a face view, somewhat enlarged, of a button embodying my design.

A represents the button, which has, at its periphery, a border *a*. Within the border *a*, 15 on the face of the button, three eagle-heads *b b b* are represented projecting from a triangular figure *c* in the center of the button.

Between the eagle-heads three eagle-tails *d* are represented, the tips of said tails terminating in close proximity to the peripheral border *a*. Slightly inwardly removed from the peripheral border small stars *e* are represented.

The leading feature of my design consists of the representation, on a button, of a series 25 of eagle-heads and interposed eagle-tails.

What I claim is—

The design for a button herein shown and described.

W. W. PIERCE.
